DESIGN FOR A SPAT

George H. Bingham, Jr., Lincoln, Mass., assignor to Cambridge Rubber Co., Cambridge, Mass., a corporation of Massachusetts

Application March 26, 1943, Serial No. 109,823

Term of patent 7 years

To all whom it may concern:

Be it known that I, George H. Bingham, Jr., a citizen of the United States, residing at Lincoln, in the county of Middlesex and Commonwealth of Massachusetts, have invented a new, original, and ornamental Design for a Spat, of which the following is a specification, reference being had to the accompanying drawing, forming a part thereof, in which

I claim:

The ornamental design for a spat, substantially as shown.

GEORGE H. BINGHAM, JR.
